UNITED STATES PATENT OFFICE.

HELENE KOMUSIN, GEB. LIEDTKE, OF BERLIN, GERMANY.

ROLLING STAMP WITH COUNTING DEVICE FOR VARIOUS PRINTING PURPOSES.

Application filed March 22, 1922. Serial No. 545,890.

To all whom it may concern:

Be it known that I, HELENE KOMUSIN, geb. LIEDTKE, a citizen of the German Republic, residing at Berlin, Germany, have invented certain new and useful Improvements in Rolling Stamps with Counting Devices for Various Printing Purposes, of which the following is a specification.

This invention relates to a rolling stamp with counting devices for various printing purposes, for instance for printing upon postal matters the amount of previously paid postage or upon legal papers of any kind the amount of duty, revenue stamps, insurance premiums or the like so that the stamps which are usually employed for this purpose can be saved.

The printing is effected in similar manner as with the otherwise used stamping or painting rollers by means of rolling, under slight pressure, over the surface to be printed, a roller upon which the signs to be printed (figures, trade marks, signs, dates, scheduling lines or the like), are marked. The roller which is movable in vertical direction in a casing and maintained in lifted position or position of rest by a spring, is controlled by a toggle lever so that said roller adopts the position for use if said toggle lever is being stretched. Each revolution of the roller at the stamping is transferred by a catch and pawl upon a counting device consisting in the well known manner of figure wheels so that the total value of the stamps printed with the apparatus is always indicated by this counting device.

The arrangement is such that the roller can be adjusted by means of an indicating hand mounted upon the stamp casing so that it executes one stamping operation only or so that it stamps continuously. In the first case the roller returns automatically to the position of rest after it has completed one revolution.

In order that the invention may be clearly understood, I shall proceed to describe the same with reference to the several forms of construction shown in the accompanying drawings, wherein:—

Fig. 1 shows the apparatus in longitudinal section, the different parts being in the normal position of rest.

Fig. 2 is a similar view showing the different parts in working position.

Figs. 3 and 4 are each a side elevation of

one of the two parts of the casing with the elements carried by these parts.

Fig. 5 is a plan view of the casing.

Figs. 6 and 7 show a part of Fig. 1 on larger scale.

Fig. 8 is a side elevation of Fig. 7.

In the construction shown in the drawings the casing is composed of two parts 1 and 2 connected the one with the other by means of angular pieces 3 upon part 2 and hook-shaped projections 4 of part 1 adapted to be hooked over the angular pieces 3. In part 1 of the casing the stamping roller 5 is journaled in vertical supports 6 movable in vertical direction. A toothed wheel 7 is keyed upon the shaft of the roller 5 and an upper toothed wheel 9 keyed upon an upper axle 8 gears with toothed wheel 7. In the middle part 6^a of the supporting frame 6 link 10 is pivoted the upper end of which is hinged to the lower end of a bell crank lever 11. The upper toothed wheel 9 carries a driver 12 which is designed to operate the control levers 13, 14, 15 of the counting mechanism. At the side of the stamping roller 5 an inking roller 16 is arranged which takes the ink from an inking pad 17. The upper end of the bell crank lever 11 projects through the top plate of the casing. When this lever 11 is being depressed the stamping roller 5, normally held in its highest position by the action of a spring 18, is lowered so that its circumference projects partly through an aperture 19 in the bottom plate of the casing (Fig. 2). The bell crank lever 11 is held in the lowered position by link 10 which has adopted a vertical position. When lever 11 is being depressed it acts upon a spring influenced rod 33 projecting from the top plate of the casing and presses the same down (Figs. 1, 3, 6 and 7). This rod 33 is guided in a sleeve 34 fixed in the upper part of the casing 1. The sleeve has lateral slots 35 in which a cross pin 36 fixed in the upper part of rod 33 is guided. A spring 38 surrounding the sleeve 34 is enclosed between a collar 37 of sleeve 34 and the cross pin 36. The bolt 33 has at its lower end a notch 39 with which engages a spring-controlled catch lever 20 to secure said bolt 33 in its lowered position. Above an angle piece 40 a mechanism is provided for the purpose of returning the stamping roller automatically to the normal position if only

one stamp has to be printed. With this ob-

ject in view two levers 20, 23 are pivotally mounted on a pin in and between the cheeks 41, 42 of said angle piece 40. Lever 23 is two-armed and its upwardly directed arm 24 has a laterally projecting tappet 25 adapted to bear against the catch lever 20. A spring 43 may be provided to hold the lever 23 in its normal position by acting upon the arm 24 to return the same to its initial position.

Upon the shaft 8 of the toothed wheel 9 a stop lever 22 is fixed. When the printing roll is lowered by the depression of lever 11 rod 33 is lowered also so that the hook-shaped upper end 45 of catch lever 20 engages with the notch 39 of rod 33. After a determined part revolution of the printing roller 5 the stop lever 22 will strike against the horizontal lever arm 23 whereby the tappet 25 of the lever arm 24 will be caused to engage the catch lever 20 and push the same back so that its hook-shaped end 45 gets out of engagement with the notch 39 of rod 33. This rod being thus released moves upward under the action of its spring 38 and lifts the bell crank lever 11 whereby spring 18 is released and returns the printing roller 5 to its normal position of rest.

If the printing roller 5 when in the lowered position is rolled over the surface to be printed its revolving movement is transmitted to the toothed wheel 9 the driver 12 of which operates at each revolution of the toothed wheel, the levers 13 and 14 and the upper end of lever 14 sliding in the fork-shaped end of the horizontal lever 15 makes this lever 15 turn in horizontal direction, so that the figure disks of the counting mechanism are operated. A window 21 is provided in the wall of the casing for observation purposes.

If only one printing has to be done the stop lever 22 upon the shaft 8 of the toothed wheel 9 strikes against the arm 23 of the lever 24. The tappet 25 is thereby caused to press against the catch lever 20 in order to disengage the same from the notch 39 of the rod 33 to allow the latter to move or jump up under the action of its spring and to thereby lift the bell crank lever 11 so that the printing roller with the toothed wheels will be returned to the upper position of rest.

The adjustment of the lever 23, 24 in the position in which it comes in contact with the lever 22, is effected with the aid of a vertical spring-controlled rod 26 (Fig. 8). The upper end of the rod 26 projects through a hole in the top-plate of the casing and is provided with a knob 28 and an indicating hand or pointer 29. At the lower and inner end of the rod 26 an arm 27 is fixed and a coiled spring is interposed between said arm 27 and the top plate of the

casing to hold the rod in its position without preventing the same from rotary movements about its axis.

The rod 26 can be set or turned to two positions indicated by A and B in Fig. 5. In the position A for single working (Figs. 1 to 7) the arm 27 of the rod 26 is out of contact with the lever 24 and the lever arm 23 is in the path of the lever 22 so that when lever 22 is turned or moved owing to the rotation of the roller 5, the lever 23 will be depressed on each rotary step of the roller 5 whereby the latter is put out of action. If, however, the rod 26 is set to the position marked by B the arm 27 will strike against the lever 24 and push the same back whereby the lever arm 23 is caused to turn out of the path of the stop lever 22. The roller 5 now is released for continuous printing.

A small boss 30 upon the top plate of the casing over which the hand 29 must move secures this hand in its position. A pawl 31 engaging with the teeth of toothed wheel 9 prevents the back revolution of the printing roll.

When the two parts 1, 2 of the casing are put together the fixed studs 32 of part 2 engage with corresponding holes of the lid of part 1 of the casing and a lead seal is fixed upon these studs so that the counting mechanism cannot be made accessible without destruction of this lead seal. Fraudulent attempts to use the apparatus for printing more stamps than are indicated by the printing mechanism are thus prevented.

According to the hereinbefore described form of construction of the invention the stamping of postal matter of any kind can be effected without the use of postage stamps, directly by the printing stamps which may be made to correspond with the value of the postage stamps which should be applied.

The spring-controlled rod 26 affords in co-operation with the lever 23, 24 the possibility of either lifting the printing roller 5, after a single printing operation from the printing position into the upper or inoperative position, or to leave the roller in the lower, operative position for continuous printing or stamping. In the Figures 2 to 7 the roller is set for a single printing operation and it will be seen, that the left-hand arm of the lever 22 is immediately above the lever 23 and about to engage the latter, the counting mechanism having just been actuated, immediately upon the beginning of the rolling action of the roller, through the driver 12, Figure 2, by means of the control levers 13, 14. On the continued rolling of the roller the lever 22 will act to engage the lever 23, to lift the lever 20 and to disengage from the lever 23 so as to be below the latter. At the next moment

the roller returns into its upper position of rest. In case that the roller again is lowered for a subsequent single printing operation, the left-hand arm of the lever 22, 5 which had actuated the lever 23, slides over the latter to assume a position below the lever 23. At the now beginning printing or stamping operation the other (right-hand) arm of the lever 22 will engage the 10 lever 23.

It will be seen that the double acting lever 22 acts to divide the roller into two like stamping faces. If the roller is desired to continuously remain in its working 15 position for subsequent stamping operations, the lever 23 is, as above explained, lifted out of the path of the lever 22. The continuous print thus made are recorded in the counting mechanism through the agency 20 of the driver 12 and the levers 13 and 14.

What I claim is:

1. An improved rolling stamp of the type described comprising in combination with a casing, a printing roller, a shaft for said 25 printing roller mounted in said casing so that it can be lowered and raised in vertical direction a support for the shaft, a spring for maintaining said roller in the normal position of rest, a toggle lever system for 30 bringing said roller to the working position and for maintaining the same in this position, a counting mechanism for registering the revolutions of said roller, a lever system controlling said counting mechanism, and a 35 toothed wheel gear connecting said printing roller with said lever system, substantially as and for the purpose set forth.

2. An improved rolling stamp of the type described comprising in combination with a 40 casing, a printing roller, a shaft for said printing roller, mounted in said casing so that it can be lowered and raised in vertical direction, a support for the shaft, a spring for maintaining said roller in the normal 45 position of rest, a toggle lever system for bringing said roller to the working position and for maintaining the same in this position, a counting mechanism for registering the revolutions of said roller a lever system 50 controlling said counting mechanism, a toothed wheel gear connecting said printing roller with said lever system, a spring influenced vertical rod mounted in said casing so that its upper end projects from the 55 top plate of the casing to be depressed when the handle of said toggle lever is lowered, designed to lift said lever and with it the printing roller after the printing of one stamp, said rod having a notch in its lower 60 part, a spring influenced catch lever bearing with its hook-shaped end against said rod and adapted to engage with said notch of the rod when said rod is lowered, a spring influenced two-armed lever pivotally mounted under said rod so that its upper arm is 65

in contact with said catch lever, and a striking lever fixed upon the axle of the upper toothed wheel of said toothed gear of the printing roller adapted to strike against the lower arm of said two-armed lever and to 70 make said lever oscillate when the printing roller has made one revolution so that the upper arm of said two-armed lever brings said catch lever out of engagement with the rod, so that this rod is released and going 75 up under the influence of its spring raises the toggle lever and consequently the printing roller, substantially as described.

3. An improved rolling stamp of the type described comprising in combination with a 80 casing, a printing roller, a shaft for said printing roller mounted in said casing so that it can be lowered and raised in vertical direction a support for the shaft, a spring for maintaining said roller in the normal 85 position of rest, a toggle lever system for bringing said roller to the working position and for maintaining the same in this position, a counting mechanism for registering 90 the revolutions of said roller, a lever system controlling said counting mechanism, a toothed wheel gear connecting said printing roller with said lever system, a spring influenced vertical rod mounted in said casing so that its upper end projects from the top 95 thereof to be depressed when the handle of said toggle lever is lowered, designed to lift said lever and with it the printing roller after the printing of one stamp, said rod having a notch in its lower part, a spring influenced catch lever bearing with its hook-shaped end against said rod and adapted to engage with said notch of the rod when said rod is lowered, a spring actuated two-armed 100 lever pivotally mounted under said rod so that its upper arm is in contact with said catch lever, a striking lever fixed upon the axle of the upper toothed wheel of said toothed gear of the printing roller adapted to strike against the lower arm of said two-armed lever, a spring influenced vertical 105 spindle mounted in said casing at the side of said rod so that it can be lowered against the action of its spring, a knob at the upper end of said spindle, a hand adjacent to knob for indicating the position of said spindle, and a lateral arm at the lower end of said spindle adapted to strike against the upper arm of said two-armed lever when said knob is being turned so that the lower arm of said 110 two-armed lever is brought out of the path of said striking lever and the printing roller can be used for continuous stamping, substantially as described.

In testimony whereof I affix my signature 115 in presence of two witnesses.

HELENE KOMUSIN, Geb. LIEDTKE.
